(57) CLAIM

The ornamental design for a drumstick holder, as shown and described.

DESCRIPTION

FIG. 1 is a perspective view from above of our new drumstick holder;

FIG. 2 is a top plan view of our new drumstick holder of FIG. 1;

FIG. 3 is a front view of our new drumstick holder of FIG. 1, the rear view being a mirror image thereof;

FIG. 4 is a view from one side of our new drumstick holder of FIG. 1; and,

FIG. 5 is an underneath view of our new drumstick holder of FIG. 1.

The broken line showing of portions of the figures is for environmental purposes only and forms no part of the claimed design.
